UNITED STATES PATENT OFFICE.

HARRY WILLIAM SMITH, OF PARAGOULD, ARKANSAS.

COLTER-CLAMP.

SPECIFICATION forming part of Letters Patent No. 623,263, dated April 18, 1899.

Application filed October 14, 1898. Serial No. 693,572. (No model.)

To all whom it may concern:

Be it known that I, HARRY WILLIAM SMITH, a citizen of the United States, residing at Paragould, in the county of Greene and State of 5 Arkansas, have invented certain new and useful Improvements in Adjustable Colter-Clamps, of which the following is a true specification.

My invention relates to adjustable colter-clamps; and its object is to provide an improved construction of the same whereby the colter may be adjusted vertically so as to vary its height with relation to the ground and also to be adjusted with respect to the 15 angle at which it strikes the ground.

The invention consists, essentially, in a colter-clamp and the novel construction and arrangements of its parts, a slotted bottom plate secured to the under side of the beam, 20 a slotted top plate secured to the upper side of the beam, provided with bolts welded or otherwise fastened to the sides and at the ends of top plate, and a clamp provided with a cross-head and a tail-nut, the construction 25 being such that by loosening the tail-nut the colter can be adjusted vertically or angularly, as hereinafter fully described and claimed.

In the accompanying drawings, Figure 1 shows a side elevation of my device. Figs. 30 2, 3, 4, and 5 show detailed views of the clamp- 30 ing mechanism.

In the said drawings the letter *a* designates bolts welded or otherwise fastened to the side and at the ends of the top plate 2, so that top 35 plate 2 sits edgewise on upper side of the beam, provided with a slot *c* lengthwise of plate, as shown in the drawings.

The clamp 3 is provided with a cross-head on the rear end, a bend at right angle far 40 enough to allow the thickness of top plate

2 and colter-shank to fit between cross-head and bend, and another bend at right angle far enough forward so that when colter-shank is drawn back as far as it will go (clamp being in slot *c*) clamp fits the colter-shank 45 snugly, the forward end of clamp projecting through slot *c* far enough to receive tail-nut *e*.

Cross-head *d* is made on rear end of the clamp 3 by lugs extending outwardly from its sides, with the inner corners of said lugs 50 rounded, so that when the tail-nut *e* is loosened the clamp releases the colter-shank.

The bottom plate 5 is formed with a slot *f* and holes *g* and is secured in place by bolts *a*, passing through the beam and holes *g*, and 55 nuts screwed on bolts *a*. Slot *f* should be even with the slot or opening through the beam.

In using the colter-clamp pass the shank of a colter up through the slot *f* in the bottom 60 plate and the opening through the beam and slip the clamp 3 in slot *c*, with the tail-nut forward. Then pass the colter-shank through the clamp 3 and secure it in place by tightening up the tail-nut *e*. To adjust the colter, 65 loosen the tail-nut *e*, move the colter up or down or back or forward to suit the ground, and then secure it in place by tightening up the tail-nut *e*.

Having thus fully described my invention, 70 what I claim is—

A top plate 2, with a longitudinal opening *c*, and formed with bolts *a*, welded or otherwise fastened to it, a clamp 3, with a cross-head *d*, and a tail-nut *e*, a bottom plate 5, 75 with slot *f* and holes *g*.

HARRY WILLIAM SMITH.
